DUPLEX RIVETING MACHINE

Lloyd A. Ward, Jackson, Mich., assignor to
Tomkins-Johnson Company, Jackson, Mich., a
corporation of Michigan

Application December 30, 1940, Serial No. 372,250

5 Claims. (Cl. 78—48)

The present invention relates to riveting machines and more particularly to riveting machines wherein the rivet is employed to punch the hole in the metal in which the rivet is disposed for heading.

Heretofore hollow rivets have been employed for punching their holes through the parts to be secured together. However, so far as is known such machines have been limited to operation on relatively soft materials such as paper and leather. The present invention is designed to rivet metal with solid rivets although the structure is equally usable for hollow rivets.

An object of the invention is to employ a rivet to punch its hole to the work to be riveted.

Another object of the invention is to provide a die and set for cooperating with the rivet to punch the work and head the rivet respectively.

Still another object of the invention is to provide a machine of the character described wherein the die and set are automatically indexed into and out of operative position respectively during the operation of the machine.

These and other objects residing in the arrangement, combination and construction of parts will be apparent from the following specification when taken with the accompanying drawings, in which

Fig. 1 is a front elevation of a portion of a riveting machine according to the present invention;

Fig. 2 is an elevation of the right side of the structure as viewed in Fig. 1;

Fig. 3 is a section on the line III—III of Fig. 2;

Fig. 4 is a section on the line IV—IV of Fig. 1, and

Fig. 5 is a section on the line V—V of Fig. 1.

Referring particularly to the drawings, the reference character 1 indicates a frame suitably supporting an anvil 2 on which is disposed a rivet 3, the anvil being provided with a suitable rivet retaining finger 4 of a character well known in the art. The frame 1 also slidably supports a ram 5 to which is connected a holder 6 and a set 7.

The holder 6 is provided with legs 8 and 9, the set 7 being secured in the leg 8 and a female punching die 10 being secured in the leg 9. The die 10 is provided with an interior passageway 11 communicating with an opening 12 in one side of the leg 9 for discharging punched slugs.

The holder 6 has projecting therethrough a supporting pin 13 which is pivoted in ears 17 and 18 depending from a slide 19 slidably arranged about the ram 1 as shown particularly in Fig. 5. The ear 17 comprises an integral extension of a cover plate 20 secured by screws 21 to the slide 19. The pin 13 is provided with a squared portion 22 intermediate its ends shown particularly in Fig. 4 for

snugly engaging with a squared opening 23 in the holder 6. The purpose of the squared portion 22 and the squared opening 23 is to rigidly secure the holder 6 and the pin 13 together for simultaneous oscillation. Secured to a squared extension 24 of the pin 13 is an indexing member 25 having a squared opening 26 therein with which the squared extension 24 cooperates for providing simultaneous oscillation of the pin 13 with the indexing member 25. Thus rotary movement of the indexing member 25 is transferred through the pin 13 to the holder 6.

For the purpose of facilitating the assembly of the pin 13 and its associated parts, the end thereof opposite the extension 24 is reduced in diameter and has secured thereto a bushing 27.

The holder 6 is provided with intersecting side surfaces 28 and 29. As shown in Fig. 1, the side surface 29 is resiliently urged against the bottom face 30 of the ram 5. The connection between the ram 5 and the holder 6 is provided by a link 31. One end of the link 31 is disposed in a slot 32 in the holder 6 and is provided with an opening 33 best shown in Fig. 3 through which the pin 13 projects. The opposite end of the link 31 extends into a longitudinal slot 34 in the ram 5 and is provided with a rectangular opening 35 best shown in Fig. 3. Adjacent the slot 35 the ram 5 is provided with a recess 36, shown particularly in Fig. 5, communicating with one side of the ram 5. A helical spring 37 is disposed in the slot 35 in the link 31 and at the same time in the recess 36 in the ram 5, the parts being arranged so that the spring 37 bears against the bottom of the recess 36 and against the top of the slot 35 so that the link 31 is resiliently urged upwardly. The upward force transferred to the link 31 by the spring 37 is exerted against the pin 13 to draw the slide 19 and with it the holder 6 upwardly. As viewed in Fig. 1 this resilient upward force holds the side surface 29 of the leg 9 of the holder 6 against the bottom face 30 of the ram 5. It will be understood that should the holder 6 be rotated about the pin 13 until the side surface 28 of the leg 8 of the holder 6 is in a horizontal position as viewed in Fig. 1, the side surface 28 will be held against the lower face 30 of the ram 5. However, as the member 6 is rotated the spring 37 will be compressed due to the tension on the link 31 at the peak 40 at the intersection of the surfaces 28 and 29 approaches and passes dead center position. It will also be obvious that when the side surface 28 is in a horizontal position, the female punching die 10 will be directed downwardly in position for cooperation with the rivet 3.

For swinging the holder 6 from one position

55

to another there are provided abutments 41 and 42 for alternately engaging with hooks 43 and 44 respectively on the indexing member 25. The abutments 41 and 42 are pivoted at points 45 and 46 respectively, to a plate 47 suitably secured to the frame 1. Abutments 41 and 42 are resiliently held in the position shown in Fig. 1 by extensible and contractable links 48 pivoted at the points 49, respectively, to the frame 1. Each line 48 consists of a rod 50 axially slidable in a tube 51. Each rod 50 is provided with spaced shoulders 52 against which are urged by a helical spring 53 loose collars 54. In neutral position the collars 54 also are urged against externally threaded nuts 55 screwed into the ends of the tubes 51. One rod 50 is connected to the abutment 42 and the other rod 50 is connected to the abutment 41. The tubes 51 are connected to the pivot points 49. It will be seen that any tendency to either extend or contract the links 48 is resisted by the springs 53.

The drawings show the set 7 in engagement with the rivet 3 having just headed the same on work 56 shown in dotted outline. As the ram 5 moves upwardly under the action of conventional driving mechanism not shown, the hook 44 moves into engagement with the abutment 42 which swings the indexing member 25 to the right as viewed in Fig. 1. As the indexing member 25 swings to the right it will draw the abutment 42 inwardly toward the axis of the ram 5 at the same time extend its extensible and contractable link 48. When the peak 40 on the holder 6 passes the dead center position sliding across the bottom face 30 of the ram 5, the resiliency of the spring 31 will cause the holder 6 to continue rotating to the right until the surface 28 of the leg 8 is against the bottom face 30 of the ram 5. As the indexing member 25 swings to the right, the hook 44 will disengage from the abutment 42 permitting the abutment 42 to resume its neutral position and the indexing member 25 will assume the position shown in dotted outline in Fig. 1 behind the abutment 41. The die 10 is now in position for cooperation with a rivet 3 on the anvil 2.

The rivet 3 is fed to the anvil 2 in some conventional manner and is held thereon by the finger 4, although it will be understood that the finger 4 is not an essential part of the invention. When the rivet 3 is in place on the anvil 2, the work 56 is held over the rivet 3 and the ram 5 is moved downwardly under the power of its actuating mechanism. The downward movement of the ram 5 drives the female die 10 into punching relation with the rivet 3, punching the rivet 3 through the work 56. The punched out slugs from the work 56 go into the internal passage 11 into the die 10 and eventually pass out of the opening 12 in the side of the leg 9 of the holder 6. As soon as the rivet 3 has been punched through the work 56, the ram returns to its upper position swinging the indexing member 25 to the left, in the manner above described, although in swinging from the right to the left the hook 43 is engaged with the abutment 41. When the indexing member 25 has been swung to the left to the position shown in full lines in Fig. 1, the set 7 is in position to head the rivet 3. Thus when the ram 5 comes down again the set 7 heads the rivet 3 on the work 56.

From the foregoing specification it will be seen that as the ram 5 reciprocates up and down, the female punching die 10 and the set 7 are alter-

nately moved respectively from inoperative to operative to inoperative position. It is preferred that the tripping mechanism for the riveting machine according to the present invention be arranged to provide the ram 5 with two downward strokes, one for punching and the other for upsetting, although it will be obvious that a separate tripping impulse may be given for each downward stroke of the ram 5.

10 Having thus described my invention, what I desire to secure by Letters Patent and claim is:

1. In a machine of the character described, a frame, an anvil for supporting a rivet, mounted in said frame, a reciprocable ram mounted in said frame, a female die for cooperating with the rivet, a set for heading the rivet, means holding said die and set in angular relation to each other, a pivotal connection between said ram and said holder whereby said holder may be swung alternately from one position to another, die and set indexing means operatively connected to said holder and movable therewith for swinging said holder, an abutment supported with respect to said frame on each side of said ram, said indexing means in one position having a portion in the path of which one of said abutments is disposed and its other position having a portion in the path of which the other of said abutments is disposed, whereby as said ram reciprocates, alternately one of said indexing means portions moves into engagement with one of said abutments to swing the indexing means and with it the holder in one direction, and the other of said indexing means portions moves into engagement with the other abutment to swing said indexing means and with it said holder in the opposite direction to alternately present said die and set to the rivet.

40 2. In a machine of the character described, a frame, an anvil for supporting a rivet mounted in said frame, a reciprocable ram mounted in said frame, said ram having a downwardly facing abutment thereon, a female die for cooperating with the rivet, a set for heading the rivet, means holding said die and set in angular relation to each other, a support for said holder, means pivoting said holder to said support, means guiding said support for movement in the direction of movement of said ram, a link connected by said pivoting means to said holder, a resilient connection between said link and said ram to resiliently draw said holder against said abutment, said holder having two intersecting faces, either one of which bears against said abutment under the action of said link, and means to oscillate said holder about the axis of said pivoting means to alternately dispose first one and then the other of said faces against said abutment, whereby as said holder is oscillated said resilient connection is extended and contracted to provide with said surfaces and abutment an over-center structure, said die and set being so arranged with respect to said surfaces that when one of said surfaces is against said abutment said die is disposed in alignment with the rivet and when the other of said surfaces is against said abutment said set is in alignment with said rivet.

3. The invention as defined in claim 2 wherein the oscillating means comprises indexing means operatively connected to the holder for oscillation therewith, and abutment means supported with respect to said frame for cooperating with said indexing means as said ram is reciprocated, whereby when said ram is reciprocated said in-

dexter is moved operatively into engagement with said abutment means to oscillate said holder to alternately present said die and set to the rivet.

4. The invention as defined in claim 1 wherein the abutments comprise pivoted arms having portions for operatively engaging the indexing means, said pivoted arms being resiliently held in predetermined positions and being swingable upon operative engagement with the indexing means to follow the movement of the same in operative direction.

5. The invention as defined in claim 2 wherein the holder oscillating means comprises indexing means operatively connected to the holder for oscillation therewith, an abutment, one on each side of said ram, supported with respect to the

frame, said abutments comprising pivoted arms having portions for operatively engaging the indexing means, said indexing means in one position having a portion in the path of which one of 5 said abutments is disposed and in its other position having a portion in the path of which the other of said abutments is disposed, said pivoted arms being resiliently held in predetermined positions and being swingable upon operative engagement with the indexing means to follow the movement of the same in operative direction, whereby as said ram reciprocates, alternately, said indexing means is swung first in one direction and then in the opposite direction to alternately present said die and set to the rivet.

LOYD A. WARD.
